UNITED STATES PATENT OFFICE.

ALBERT SABATH, OF CHICAGO, ILLINOIS, ASSIGNOR TO SCENE-IN-ACTION CORPORATION, OF CHICAGO, ILLINOIS, A CORPORATION OF ILLINOIS.

DESIGN FOR A LAMP OR SIMILAR ARTICLE.

Application filed December 29, 1927. Serial No. 24,687. Term of patent 3½ years.

To all whom it may concern:

Be it known that I, ALBERT SABATH, a citizen of the United States, residing at Chicago, in the county of Cook and State of Illinois, have invented a new, original, and ornamental Design for Lamps or Similar Articles, of which the following is a specification, reference being had to the accompanying drawing, forming part thereof.

The figure is a side elevation of a lamp showing my new design.

I claim:

The ornamental design for a lamp or similar article as shown.

ALBERT SABATH.
